(57) **CLAIM**

The ornamental design for a handle for soap, as shown and described.

DESCRIPTION

FIG. 1 is a front perspective view an embodiment of the design. The rear perspective view is a mirror image of the front perspective view.

FIG. 2 is a right side elevational view thereof. The left side elevational view is a mirror image of the right side elevational view.

FIG. 3 is a top plan view thereof; and,

FIG. 4 is a front elevational view of an embodiment of the design. The rear elevational view is a mirror image of the front elevational view.

The broken-line disclosure of the soap bar in the views is for illustrative purposes only and forms no part of the claimed design.
